UNITED STATES PATENT OFFICE.

CHARLES E. WAREAM, OF CINCINNATI, OHIO, ASSIGNOR TO THE AMERICAN LAUNDRY MACHINERY COMPANY, OF CINCINNATI, OHIO, A CORPORATION OF OHIO.

IRONING MACHINE.

Application filed December 23, 1921. Serial No. 524,413.

To all whom it may concern:

Be it known that I, CHARLES E. WAREAM, a citizen of the United States, residing at Cincinnati, in the county of Hamilton and State of Ohio, have invented certain new and useful Improvements in Ironing Machines, of which the following is a specification.

This invention relates to improvements in ironing machines.

The objects of this invention are to provide an ironing machine with means whereby the work can be discharged after a certain degree of ironing or can be subjected to further ironing before being discharged; to provide means adjustable by the operator at any time during the operation of the machine for determining the degree of ironing of the different classes of work; to provide such means which is adapted to cause all of the work to be discharged at the same end of the machine; and to provide such a means which is capable of manipulation from either end of the machine.

Other objects will be apparent from the following description and claims when considered together with the accompanying drawings.

Fig. 1 is a longitudinal sectional view of an ironing machine with my improved attachment; Fig. 2 is an enlarged end elevation showing the doffer plate attached to the machine; Fig. 3 is an enlarged plan view of the doffer plate attachment; and Fig. 4 is a detail sectional view showing the means of mounting the doffer plate.

The present illustration shows a well known type of flat work ironer in which the main supporting frame is indicated by reference numeral 1 and the steam chest supported thereby by reference numeral 2, while the padded rolls for feeding the work along the chest are indicated by reference numeral 3. As will be understood, the work is fed into one end of the machine over the endless feeding apron 4 and is discharged from the other end of the machine on to the receiving table 5. The endless apron 6 extends about the rollers 7, this apron passing along the under face of the chest 2. The endless apron 8 extends about the rollers 9 and has surface engagement with the apron 6. The apron 8 extends also about the roller 10 at which point the work is discharged on to the receiving table 5.

This structure will be recognized as a well known type of flat work ironer to which my improved doffer plate is applied.

The doffer plate 11 is of angular form and of any suitable material, and its supporting members 12 secured thereto are in turn rotatably mounted upon the bushing members 13. The bushings 13 are secured in the arms 14 of the frame by means of set screws 15 and serve also as journal bearings for the shaft ends 7' of the roller 7 at the discharge end of the chest 2. By means of the handle 16, which is formed integral with or otherwise suitably attached to the supporting members 12, the doffer plate can be made to assume either one of two positions, as indicated by full and dotted lines in Figs. 1 and 2. The rod 18 extends from the handle 16 to the handle 19 pivoted on the frame at the other end of the machine so that the doffer plate can be adjusted by the operator from either end of the machine. The doffer plate is of such proportions that when moved to full line position, its one edge will engage the end portion of the chest 2 and will serve to strip or direct the work from between the last feeding roller and the chest so that it will be discharged directly on to the receiving table 5. The doffer plate is set in full line position for such work as under-garments and the like which are ironed only by passing the same along the top surface of the steam chest 2. In cases of flat work such as table linen, etc., the doffer plate is moved to occupy dotted line position so as to deflect the work as it emerges from between the last feeding roller and the steam chest and cause the same to pass between the apron 6 and the lower face of the steam chest, so as to receive further ironing. The work will then be conveyed between the aprons 6 and 8 and finally carried by the apron 8 over the roller 10 and discharged on to the receiving table 5. The doffer plate can be adjusted to either of its two positions at any time during the ironing operation according to the class of work which might be passing through the machine at any given time. In this way the particular class of work can be given the proper ironing without interruption of the machine and at the same time will discharge all of the work from the same end of the machine on to the receiving table 5. Thus the efficiency of

such an ironing machine is increased with respect to its capacity as well as with respect to the class of work performed.

It is to be understood that the present disclosure is merely for purposes of illustration and that modifications of the same might be made without departing from the spirit of this invention. For instance, if found necessary, means may be provided for locking the doffer plate in the position to which it is set. It is also possible to provide an operating handle on each side of the machine for convenience to the operator, if so desired. Modifications might also be made in the particular form of the doffer plate itself, all within the spirit of the present disclosure.

What I claim is:

1. In a ironing machine, the combination of means for performing a plurality of successive ironing operations upon given materials, said machine being adapted to receive the materials at one point and to discharge the same at another point, of means for selectively causing the materials to be discharged at said discharge point after the first ironing operation or to be subjected to further ironing and then discharged at said point of discharge, said means being operable from both the receiving and discharge points of said machine.
2. In an ironing machine, the combination of an ironing chest, a plurality of rolls arranged for feeding the work over said

chest for an ironing operation, a chest conveyor arranged at the discharge end of said ironing chest and adapted to feed the work along the lower face of said chest for a further ironing operation, a delivery conveyor for receiving the work, and means arranged at the discharge end of said ironing chest for directing the work to the delivery conveyor after the first ironing operation or to the chest conveyor for a further ironing operation before being delivered to said delivery conveyor.

3. In an ironing machine, the combination of an ironing chest, a plurality of ironing rolls arranged for feeding the work over said chest for an ironing operation, a chest conveyor arranged about a roller adjacent the discharge end of said chest and adapted to feed the work along the lower face of said chest for a further ironing operation, a delivery conveyor for receiving the work, and a doffer plate arranged above the roller about which the chest conveyor travels and extending beyond each side of said roller to direct the work from the ironing chest either directly to the delivery conveyor after the first ironing operation or to the chest conveyor for a further ironing operation before being delivered to said delivery conveyor.

In testimony whereof I hereby affix my signature.

CHARLES E. WAREAM.
